UNITED STATES PATENT OFFICE

2,029,340

MANUFACTURE OF BAGS

Thomas M. Royal, Philadelphia, Pa.

Application July 28, 1932, Serial No. 625,375

10 Claims. (Cl. 93—35)

My invention relates to the manufacture of bags and similar containers of paper and similar material and comprises an improved method of and means for preparing or associating a plurality of individual webs of paper or similar material subsequently developed into tube formation in bag-making machines; the tube or tubes thus formed being severed into blanks of any predetermined and uniform length, which blanks are passed through bottoming mechanism and are finally delivered as finished bags. A further feature of my invention is the development of a special type of tubular blanks from a plurality of webs or plies of paper or similar material.

In the manufacture of paper bags for packaged goods it is common practice to print upon the paper web from which such bags are produced indicia representing the contents of the bag or package, the name of the dealer or proprietor, trade-mark data, etc., etc., such printed matter being applied successively to such web in spaced relation, so that when a printed web is subsequently run through a bag-making machine and formed into a tube from which bags are subsequently finished, unit blanks may be cut from such tube in properly spaced relation with respect to such printed matter and subsequently formed into bags. This is well known practice and millions of bags are made in this manner, including many types of lined bags which, besides serving to keep the contents relatively fresh, prevent the staining of the outer or cover sheet or web of the bag or package with essential oils present in the goods contained therein.

In the printing of what may be termed the outer or cover portion of the bag or package it is necessary, unless very fast drying ink is employed and the use of the same presents objections difficult to overcome, to provide what is known as a slip sheet; usually a sheet of such nature as to prevent a set-off of the printed surface upon the back of the printed web, and this sheet is wound with the printed web and overlies the printed surface of the same. When a roll of the printed web was to be presented to the bag-making machine, it was necessary to remove the slip sheet and in practically all instances, after the ink has dried, the printed sheet is rerolled for the purpose of removing the slip sheet, which is also rerolled on a separate mandrel for further use. As may be readily understood, this operation increases very materially the amount of work necessary to transform the printed sheet or web into bags.

At the present time there is a demand for

packages enclosed in "Cellophane", usually that of the waterproof type, with a view of not only preserving the freshness of the packaged contents, but of making the package more attractive. Some attempts have been made to carry a web of "Cellophane" through the bag-making machine along with the printed web, but many difficulties have been encountered which preclude the satisfactory manufacture of bags when attempts are made to associate three separate webs; 10 the cover paper; the thin "Cellophane" sheet lying on top of the same, and the bag lining paper disposed on the opposite or inner side of the printed web, and pass them through a bag-making machine.

My invention comprises employment of a sheet of "Cellophane", which may form the outer and transparent layer or ply of the finished bag and/or package, and the permanent association of the same with the printed web which, heretofore, 20 has usually been the outer wall or ply of a lined bag. The web or ply of "Cellophane" is presented to the printed web as the latter is wound upon a mandrel or core and overlies the printed surface in direct contact with the printing ink. 25 In some instances the ink may be sufficiently adhesive to insure such permanent contact of the "Cellophane" with the printed surface as to preclude the necessity of otherwise securing these two webs together or, if desired, suitable areas 30 of the printed web beyond the printed portion thereof may be coated with adhesive so as to insure proper and permanent engagement of the web of "Cellophane" therewith. The same effect may be accomplished by supplying the ink with 35 an adhesive ingredient.

The several features of my invention are more fully referred to hereinafter; reference being had to the accompanying drawings, more or less diagrammatic in character, in which:

Figure 1 is a diagrammatic view of means which may be employed for forming a compound web from which bags may be formed; such web consisting of a printed ply of paper to constitute the body of a bag and a sheet or ply of "Cellophane" which is associated with the printed ply of paper and forms a transparent cover for the finished bag.

Fig. 2 is a perspective view illustrating the manner in which the web of paper and the web of "Cellophane" are rolled together.

Fig. 3 is an enlarged sectional view of a duplex web of bag-making material comprising the paper ply and the sheet or ply of "Cellophane".

Fig. 4 is a view similar to Fig. 3, showing a 58

sheet of lining paper associated with the duplex web.

Fig. 5 is an enlarged sectional view of the wall at the open end of a tubular blank made from the duplex web and subsequently formed into a bag.

Fig. 6 is a similar view illustrating a sheet of lining material associated with the duplex-web.

Fig. 7 is a cross sectional view of a double-walled tube from which bags may be made in accordance with my invention, and

Fig. 8 is a perspective view of a package formed from a bag or container made from a triplex web developed in accordance with my invention.

15 In the drawings, 1 represents a roll of bag paper to be printed. This may be passed over guide rolls 2 and 3, and over a platen roll 4, associated with printing means of single or multiple type, depending upon the number of colors applied, and 20 thence to a core 5 upon which such paper in its printed condition is rewound. Any suitable form of printing means may be employed, the printing rolls being indicated at 6. Under usual circumstances in the practice heretofore followed, the 25 core 5 receives the printed web or sheet and a second web or sheet; the two webs or sheets being wound together and the second sheet separating the printed surface of the printed web from the back of the same throughout the successive convolutions wound therewith.

30 In carrying out my invention I employ a web or sheet of "Cellophane" indicated at 10 as the second sheet or web, and such "Cellophane" web or sheet may be delivered from a roll 11. The web 35 or sheet of "Cellophane" is wound with the printed web or sheet on the core 5 in a manner substantially identical with the use of slip sheets heretofore employed, excepting that the "Cellophane" is permanently associated with the printed web or sheet. For this purpose the printed web may be provided with areas of adhesive applied at regular intervals; suitable means of a type well known in the art being arranged to apply such adhesive to the surface of the printed 45 web beyond or adjacent to or as part of the printed portion thereof. As is well known such means may comprise the use of an adhesive supplied in the printing ink and applied to predetermined portions of the web as certain parts of the indicia are printed thereon; the use of an ink which is of itself suitably adhesive; or adhesive alone 50 may be applied to predetermined parts of the web in any suitable and well known manner.

55 The compound web consisting of the paper cover sheet or sheet with the imprint thereon and the "Cellophane" web or sheet which serves as the protector for the printed surface, may then be removed from the printing and winding mechanism and introduced into proper position with respect to a bag-making machine whereby bags 60 with or without the addition of the liner may be produced.

65 Fig. 2 shows the manner in which the "Cellophane" web or sheet is associated with the printed web. These webs or sheets are of substantially the same width and when rolled together they are guided or directed so as to overlap at opposite edges, as clearly illustrated at *a* and *b*; such overlapping arrangement providing for the securing of edge portions of each 70 of the plies separately at the overlapping seam of the bag, as indicated in Fig. 7; lines or areas of suitable adhesive being applied to the surface of the respective plies at one side or edge of the 75 same, as indicated at *a'* and *b'*.

In making the combined web comprising the sheet or ply of bag body paper and the sheet or ply of "Cellophane" constituting the cover or wrap it is desirable to join these webs together at intervals corresponding to the length of bag blanks formed from the tubular structure into which the duplex web is shaped in the bag-forming machine. Various ways of securing the plies of the duplex web together may be employed; the adhesive may be applied over successive areas corresponding to the blank lengths in spots at regular or irregular intervals, or in parallel lines over such areas, or in other ways. I prefer, however, to connect these plies or webs together by broad or relatively broad bands of adhesive disposed at regularly succeeding intervals as indicated at *x*, in Figs. 2, 3, et seq., so that when blanks are cut from the tube into which such duplex web is formed and such blanks subsequently formed into bags, the duplex walls (or triplex walls when a liner ply is employed) will be in permanent contact and present single edges at the opposite ends of the blank from which a bag is made. Additionally, such condition facilitates use of the bag when being filled with any commodity.

25 The broad bands of adhesive may be of any colorless cementitious material capable of performing the desired function, or such adhesive may be combined with ink so that the broad connecting bands are in the nature of ornamentation applied to the bags as part of or associated with the printed matter applied thereto as indicating the contents of the bag—advertising matter, etc.

30 By having complete or substantially complete bands of adhesive applied to the compound web for the purpose of securing the plies of the same together at bag length intervals, the tubes made from such compound webs are more readily cut into the desired blanks inasmuch as the severing blade has a firmer wall to engage than if the two 40 or three separate plies plus the seams were being engaged, and a cleaner cut is insured.

35 The securing of the two sheets or webs together, one of which may be "Cellophane", by the bands of adhesive disposed at bag length intervals is of further value in connection with the appearance of the bag inasmuch as the "Cellophane" appears in the finished package as a final covering or wrapper and not as a mere glazing or varnishing of the ply which may be termed the 45 body web.

40 While the securing together of the separate webs or plies may be effected by other means than the broad bands of adhesive, they are particularly desirable in view of the type of bag employed inasmuch as the wall portions engaged by the adhesive at one end of the blanks will be folded in when the bag is filled, and such portion may be fully folded in with the bottom formation.

45 If and when a liner ply is employed in the formation of a bag, this may be arranged to project at one side of the multiple plies so as to be secured at the seam portion of the finished bag—paste being applied to such liner or not as may be desired.

50 The zones of contact provided by the adhesive between the ply of body paper and the transparent outer cover are relatively wide and the tube is severed into blanks by transverse cutting means 55 passing through such zones at some point intermediate the termini of their area lengthwise of the blank so that the open end of the finished bag will present substantially a single wall;

greatly facilitating the introduction of material to be contained within such bags.

In Fig. 8, I have shown a package made of my improved composite web and a liner, in which A represents the outer enclosure of "Cellophane", and B the usual printed cover paper of the package or bag; these two layers constituting the compound web which may be secured together by the broad bands of adhesive such as indicated 10 at x. The liner section forming the inner layer or ply of the wall is shown at C.

It will be understood, of course, that many products to be packaged substantially in the manner indicated do not contain sufficient oily constituents to stain the wrapper, and with such products it may be possible to employ bags without a liner.

While in some instances ordinary "Cellophane" may be employed with entirely satisfactory results, I prefer to employ "Cellophane" of the waterproof type, designed to produce a substantially water- or moisture-proof package; such "Cellophane" enclosure additionally serving to protect the contents thereof and maintain its 25 freshness, besides giving an ornamental appearance or finish.

While I have illustrated a particular embodiment of my invention it will be understood that I do not wish to be limited to the exact arrangement disclosed and that modifications thereof may be made without departing from the spirit of my invention and the scope of the appended 30 claims.

I claim:

1. In the preparation of multi-ply webs for the manufacture of multiwall paper bags, producing a printed web in continuous lengths, associating therewith a web of transparent material in continuous lengths and in direct contact with said 40 printed surface, and causing said transparent web to be maintained in fixed position with respect to said printed web for subsequent formation into multiwall bags by the application of adhesive to said printed web prior to the association therewith of the transparent web; said webs being laterally spaced with respect to each other with one edge of the paper web projecting beyond the adjacent edge of the transparent web and one edge of the transparent web projecting beyond 45 the adjacent edge of the paper web.

2. In the preparation of multi-ply webs for the manufacture of multiwall paper bags, producing a printed web in continuous lengths, associating therewith a web of transparent material in continuous lengths and in direct contact with said 55 printed surface, and causing said transparent web to be maintained in fixed position with respect to said printed web for subsequent formation into multiwall bags by the application of adhesive to said printed web simultaneously with the printing operation; said webs being laterally spaced with respect to each other with one edge of the paper web projecting beyond the adjacent edge of the transparent web and one edge of the transparent web projecting beyond the adjacent edge of the paper web.

3. In the manufacture of multiwall paper bags, the step of producing multi-ply material from which such bags are made, which consists in 60 passing a web of material in continuous lengths in contact with an impression or printing surface, reeling said web after the printing operation, providing said printed surface with adhesive material, and associating with said adhesive prepared printed surface a continuous web

of transparent material for permanent engagement with said printed surface; said webs being laterally spaced with respect to each other with one edge of the paper web projecting beyond the adjacent edge of the transparent web and one edge of the transparent web projecting beyond 65 the adjacent edge of the paper web.

4. In the manufacture of multiwall paper bags, the step of producing multi-ply material from which such bags are made, which consists in 10 passing a web of material in continuous lengths in contact with an impression or printing surface, reeling said web after the printing operation, providing said printed surface with adhesive material simultaneously with the printing operation, and associating with said adhesive prepared printed surface a continuous web of transparent material for permanent engagement with said printed surface; said transparent web being reeled with the printed web and said webs being 15 laterally spaced with respect to each other with one edge of the paper web projecting beyond the adjacent edge of the transparent web and one edge of the transparent web projecting beyond 20 the adjacent edge of the paper web.

5. In the manufacture of paper bags, means for printing a continuous web of paper, means for applying broad bands of adhesive to said printed surface, means for directing a continuous web of "Cellophane" into intimate contact with the 30 printed surface and said bands of adhesive for permanent association with said printed web, and means for simultaneously reeling together said webs of paper and "Cellophane"; said webs being laterally spaced with respect to each other with 35 one edge of the paper web projecting beyond the adjacent edge of the "Cellophane" web and one edge of the "Cellophane" web projecting beyond the adjacent edge of the paper web.

6. The method of making multi-ply webs for 40 use in the manufacture of multiwall bags, which comprises continuously printing a web of paper, passing the same to a core or mandrel upon which it is wound, and simultaneously winding therewith a web of transparent material; said 45 transparent web being permanently attached to the printed web over the printed matter thereon and said webs being laterally spaced with respect to each other with one edge of the paper web projecting beyond the adjacent edge of the transparent web and one edge of the transparent web projecting beyond the adjacent edge of the paper web.

7. The method of making multi-ply webs for 50 use in the manufacture of multiwall bags, which 55 comprises continuously printing a web of paper, applying areas of adhesive at regularly succeeding intervals in association with the printed matter, passing such prepared web to a core or mandrel upon which it is wound, and simultaneously 60 winding therewith a web of transparent material; said transparent web being permanently attached to the printed web over the printed matter thereon by such adhesive and said webs being laterally spaced with respect to each other with 65 one edge of the paper web projecting beyond the adjacent edge of the transparent web and one edge of the transparent web projecting beyond the adjacent edge of the paper web.

8. The method of making multi-ply webs for 70 use in the manufacture of multiwall bags, which comprises continuously printing a web of paper, passing the same to a core or mandrel upon which it is wound, simultaneously winding therewith a web of "Cellophane", and permanently 75

attaching said "Cellophane" to the printed web over the printed matter thereon; said "Cellophane" web forming a transparent outer sheath for bags produced from said multi-ply web and said webs being laterally spaced with respect to each other with one edge of the paper web projecting beyond the adjacent edge of the "Cellophane" web and one edge of the "Cellophane" web projecting beyond the adjacent edge of the paper web.

9. The method of making multi-ply webs for use in the manufacture of multiwall bags, which comprises continuously printing a web of paper, applying areas of adhesive at regular intervals in association with the printed matter, passing such prepared web to a core or mandrel upon which it is wound, simultaneously winding therewith a web of "Cellophane", and permanently attaching said "Cellophane" web to the printed web over the printed matter thereon by such

adhesive; said "Cellophane" web forming a transparent outer sheath for bags produced from said multi-ply web and said webs being laterally spaced with respect to each other with one edge of the paper web projecting beyond the adjacent edge of the "Cellophane" web and one edge of the "Cellophane" web projecting beyond the adjacent edge of the paper web.

10. The method of making multi-ply webs for use in the manufacture of multiwall bags, which comprises continuously printing a web of paper, passing the same to a core or mandrel upon which it is wound, and simultaneously winding therewith a web of transparent material; said transparent web being permanently attached to the printed web over the printed matter thereon and said webs being laterally spaced with respect to each other to provide single ply projections at opposite edges of the multi-ply web.

THOMAS M. ROYAL.
